TOBACCO PRODUCT

Abraham Bayley, Bon Air, and Frank E. Resnik and Ernest W. Robb II, Richmond, Va., assignors to Philip Morris Incorporated, New York, N.Y., a corporation of Virginia
No Drawing. Filed Oct. 24, 1962, Ser. No. 232,865
8 Claims. (Cl. 131—17)

This invention relates to tobacco products. More particularly it relates to tobacco products which upon smoking have enhanced characteristics of flavor and aroma.

It has long been common to alter, enhance and improve the flavor and aroma of tobacco products by incorporating therein by various methods a variety of flavoring and other ingredients. Sugar, licorices and other constituents have frequently been used for this purpose, and it has also been suggested to incorporate more uncommon flavorings on the leaf or even to inject them within the living plant. Many aroma and flavor enhancing conditions which confer desirable enhancement of the smoke aerosol when the tobacco product is burned cannot suitably be used by reason of their volatility, instability or other considerations. Such an ingredient is cinnamic acid. Its storage stability has been found to be quite low, and as a result its inclusion in tobacco products at the time of manufacture is not considered worthwhile because the contribution which it makes to the smoke at the time of use by the consumer is greatly diminished.

We have now discovered that cinnamic acid can be contributed to the smoke aerosol upon pyrolysis by incorporating in the tobacco product prior to smoking a small but effective amount of a dimer of cinnamic acid, said dimer being characterized in releasing cinnamic acid below the pyrolysis temperature of tobacco. In particular, we have found that the smoke of tobacco products may be enhanced by incorporating therein at least one member of the group consisting of truxillic acids and truxinic acids. α -truxillic acid and β -truxinic acid are particularly preferred.

It is known in the art that cinnamic acid polymerizes under irradiation with strong intensity light to its stereoisomeric dimers, and particularly to α -truxillic and β -truxinic acids. We have found that cinnamic acid dimers when incorporated in tobacco products decompose under pyrolytic smoking temperature into cinnamic acid and in some instances small amounts of other substances which are innocuous. The dimers of cinnamic acid are non-volatile and have no odor and consequently do not contribute undesirable odors to the product during storage or before use. They are stable under storage conditions and are non-reactive. Upon thermal degradation during pyrolysis, however, they release cinnamic acid into the aerosol smoke phase.

The reaction to form dimers of cinnamic acid is known and does not form any part of this invention. The reaction can be illustrated as follows:

The thermal degradation accompanying pyrolysis is essentially the reverse of the reactions just set forth. It is to be understood that the particular stereoisomeric forms illustrated in the foregoing equations are not intended as

2

limitative of the invention and that by "truxillic acids" we mean any of the isomeric forms of the 2,4-diphenylcyclobutane-1,3-dicarboxylic acids, including the "truxinic acids," by which we mean any of the corresponding 3,4-diphenyl-1,2-dicarboxylic acids.

The presence in the smoke aerosol in small but effective amounts of cinnamic acid in either its cis or trans forms contributes a subtle and desirable flavor and aroma of cinnamon to the smoke. The amounts of dimer incorporated in the tobacco product is not critical and may be selected by one skilled in the art according to the subtlety or distinctness of the cinnamon note desired to be imparted, and the amount may well be related to the nature and amounts of other flavoring or aroma-producing constituents in a particular mix. Generally, we have found that from about 1 to about 10 mg. of dimer per gram of tobacco product is a desirable and appropriate range.

Derivatives of cinnamic acid which are characterized in imparting flavor and/or aroma to smoke may also be incorporated in tobacco products in the form of their dimers in accordance with the invention. Illustrative derivatives include the lower alkyl (up to about 6 carbon atoms) and aryl esters of cinnamic acid. Dimers of the methyl, ethyl and benzyl esters of cinnamic acid are particularly preferred.

The following examples are intended to be illustrative of the invention and are not to be taken in a limiting sense. All parts are by weight except as otherwise specified.

Example 1

Trans-cinnamic acid is irradiated for 120 hours under a General Electric H3F high pressure mercury arc lamp giving strong radiation at 290 μ . The product is dried in a desiccator and analyzed on a Cary 11 spectrophotometer. None of the starting material is identified as present in the product. Photodimerization is found to have taken place with the formation of α -truxillic and β -truxinic acids as the greatly predominant products.

2 grams of the product is pyrolyzed in a 30 x 180 mm. Vycor tube packed with porcelain saddles and heated in an electric furnace, under the following reaction conditions: nitrogen flow 600 ml. per second, residence time 3 seconds, reaction temperature 500° C. $\pm$ 10°, rate of addition 0.10 g. per minute. A yield of 1.38 g. of crude pyrolysis product is collected in a trap cooled by Dry Ice-acetone and is dissolved in ether and esterified with ethereal diazomethane. The methylated solution is examined by gas chromatography, using an F&M model 500 instrument with a 2 foot x $\frac{1}{4}$ inch column of 20% Carbax on firebrick, column temperature 175° C., carrier gas flow rate 68 ml. per minute.

Only three peaks are observed on the chromatogram. The three components are identified by trapping the exit gases corresponding to each peak and measuring the ultraviolet absorption spectrum of the methanol solutions. The three pyrolysis products are thus identified as cis-cinnamic acid, trans-cinnamic acid and cis-stilbene. The identifications are confirmed by comparing the chromatographic retention times of known reference samples of these three products with the retention times of the pyrolysis products. The yields from the two gram sample of α -truxillic acid and β -truxinic acid mixture are calculated from the areas under the peaks of the gas chromatogram using calibration curves prepared from known reference samples as follows:

	G.
Trans-cinnamic acid	1.05
Cis-cinnamic acid	0.17
Cis-stilbene	0.01

Example 2

Regular cigarette filler is sprayed with 4% corn syrup and divided into two parts, one being a control. To the other portion is added the photodimerization product obtained in Example 1, with mixing in a Blender. Hand-made cigarettes are then prepared from both batches, the cigarettes weighing 1.2 grams each and the test group containing 1 mg. of the mixed truxillic acid dimers.

The cigarettes are smoked in a machine under standard conditions (70 mm. cigarettes smoked to a 20 mm. butt at 35 cc. volume puffs of 2-second duration at intervals of one puff per minute). The smoke from the cigarettes is collected in a gas phase collection smoking machine at liquid nitrogen temperature and analyzed spectrophotometrically. The smoke of the test cigarettes is found to contain significant amounts of cinnamic acid. All the other smoke components are substantially the same in both the test and control cigarettes. The amount of cinnamic acid transferred to the smoke aerosol phase of the test cigarettes ranges from 14 to 19 γ (micrograms) per cigarette, the average being 17 γ per cigarette. The smoke from the controls contains no cinnamic acid.

Subjective tests of the two groups of cigarettes by a panel of smokers shows that the groups are readily distinguishable and that a definite and pleasing flavor of cinnamon is detected in the smoke of the test cigarettes.

Example 3

The procedure of Example 2 is repeated with the exception that each of the test cigarettes contains 10 mg. of cinnamic acid dimer. The amount of cinnamic acid found in the aerosol smoke phase of the test cigarettes ranges from 73 to 99 γ per cigarette, the average level being 89 γ per cigarette.

The presence of a cinnamon note in the smoke of the test cigarettes is somewhat more pronounced than in the smoke of the cigarettes prepared in Example 2.

Example 4

Ethyl cinnamate is irradiated at room temperature for 60 hours according to the procedure of Example 1. Analysis of the product shows it to be substantially ethyl α -truxillate (melting point 144-146° C.).

The ester is pyrolyzed at 500° C. according to the procedure of Example 1. The liquid pyrolysate, obtained in a yield of 65%, is examined by gas chromatography with a 10 ft. Carbowax column at 200° C. Two peaks are observed in the curve and the corresponding components are separately collected in traps. The principal component comprising about 90% of the pyrolysate is identified by infrared and ultraviolet spectroscopy as

ethyl trans-cinnamate; the minor component comprising about 10% of the mixture is similarly identified as ethyl cis-cinnamate. No other pyrolysis products are observed.

Test cigarettes containing between 1 and 10 milligrams each of ethyl α -truxillate are smoked by a panel of smokers and a pleasing cinnamon-type note, distinct from that of the test cigarettes of the foregoing examples, is detected.

Example 5

10 Dimers of lower alkyl esters of cinnamic acid and dimers of aryl esters of cinnamic acid are prepared and incorporated in cigarettes in amounts between about 1 and 10 milligrams per cigarette. Pleasing flavor notes are detected in the smoke of the cigarettes so prepared.

15 It is to be understood that dimers of cinnamic acid and its alkyl and aryl derivatives may be employed in accordance with the invention without regard to the manner of their preparation and that the invention does not depend upon the preparative steps hereinabove described.

20 Mixtures of such dimers may be incorporated in tobacco products, and they may be blended with still other flavorings in manners known to the art.

We claim:

25 1. A tobacco product having incorporated therein a dimer of a member of the group consisting of cinnamic acid and its lower alkyl and aryl derivatives.

2. A tobacco product according to claim 1 wherein the amount of dimer is between about 1-10 mg. per gram of tobacco product.

30 3. A tobacco product having incorporated therein a member of the group consisting of a truxillic acid and the lower alkyl and aryl esters thereof.

35 4. A tobacco product having incorporated therein a member of the group consisting of 2,4-diphenylcyclobutane-1,3-dicarboxylic acids, the corresponding 3,4-diphenyl-1,2-dicarboxylic acids and the lower alkyl and aryl esters of said acids.

40 5. A tobacco product having incorporated therein α -truxillic acid.

6. A tobacco product having incorporated therein β -truxinic acid.

45 7. A method of enhancing the flavor of the smoke of a tobacco product, which comprises incorporating with said tobacco product prior to smoking a small but effective amount of a dimer of a member of the group consisting of cinnamic acid and its lower alkyl and aryl derivatives.

50 8. A method according to claim 7, wherein the amount of said dimer is between about 1-10 mg. per gram of tobacco product.
